UNITED STATES PATENT OFFICE.

EDWARD E. KALLENBACH, OF NEW YORK, N. Y.

FILLING MACHINE.

Application filed May 10, 1924. Serial No. 712,324.

To all whom it may concern:

Be it known that I, EDWARD E. KALLENBACH, a citizen of the United States, residing in New York, in the county and State of New York, have invented certain new and useful Improvements in Filling Machines, of which the following is a specification.

This invention relates to bottle or tube filling machines, in general and more especially to machines for automatically filling tubes with toilet creams, such as dental creams, facial creams, shaving creams and the like.

Among the objects of the present invention it is aimed to provide improved means for discharging or delivering to a receiving conveyor or container the bottles or tubes that have been filled by a filling machine or the like.

It is a further object of the present invention to provide an improved discharge or delivery from a carrier such as a turret or turntable adapted to carry tubes, containers or the like to the different stages of treatment, and by means of which discharge or delivery the filling tube or container can be automatically delivered from the turret or turntable to a common receiver or container.

Specifically, the present invention contemplates the provision of an improved discharge or delivery from a turret or turntable having tubular seats or sockets for receiving a plurality of tubes, containers or the like to be filled and closed while being carried around by said turntable, by means of which discharge or delivery, the tube or container, after being filled and closed, may automatically be lifted out of the tubular holders or sockets on the turntable and delivered to a common receiver or container.

These and other features, capabilities and advantages of the present invention will appear from the subjoined detail description of one specific embodiment thereof illustrated in the accompanying drawings in which,

Figure 1 is a fragmental plan of the devices constituting one embodiment of the present invention.

Fig. 2 is a side elevation of part of the devices illustrated in Fig. 1.

Figs. 3, 4 and 5 are fragmental end elevations illustrating successive positions of

the gripping claw or clamping member in its act of gripping and releasing a tube.

Fig. 6 is a detailed view of a lever forming part of the actuating means for the gripping claw.

Fig. 7 is a fragmental plan of the gripping claw.

Fig. 8 is an end view of the active end of the lever illustrated in Fig. 6.

The present invention is illustrated as associated with a standard filling machine for filling standard toilet cream container tubes with a toilet cream, such as a dental cream, facial cream, shaving cream or the like and subsequently closing the bottom ends of such tubes, the mouths proper of the tubes having previously been closed by caps. With such standard machines as illustrated, there is provided a carrier such as the turret or turntable 1 rotatably mounted on a vertical shaft 2, and having a plurality of radially extending brackets 3 secured to the peripheral edge of the turntable 1 and having horizontally extending supports 4 on which there are formed seats, such as the cylindrical receivers 5.

The turntable 1 is intermittently rotated causing the turntable and its supports 4 intermittently to come to positions of rest so that the supports 4 may successively come to positions of rest where they receive inverted tubes 6, with their capped ends extending downwardly, then subsequently come into positions of rest beneath the pump 7 where the toilet cream is being dispensed, then subsequently come into positions of rest where the closing dies 8 and 9 are caused to co-act with one another to collapse the bottom ends of the tubes and form on each tube a flange 10 folded over upon itself, and then subsequently come into positions of rest beneath the gripper or gripping member 11, where the gripping member 11 will grip each tube 6, lift it from the container 5 and deliver it to the receiving platform, the inclined chute 12 to be fed to a common receiver or container.

The gripping member 11 now to be described and the actuating parts of the same constitute the main parts of the present invention.

Extending across the turntable 1, there is provided the arched bracket 13 having two arms 14 and 15 which are secured at their inner ends to the upright member 16

in the present instance consisting of two sections 17 and 18. To the lower end of the section 17, in the present instance, there is secured the horizontally extending arm 19, to the front free end of which is fixed the depending member 20 having the laterally extending stop ears 21 and 22 at its lower end. Adjacent to the depending member 20 and just to the rear thereof the arm 19 is provided with an opening to receive the pin 23 which has a collar 24 secured thereto and resting on the upper face of the arm 19. The upper end of the pin 23 extends through an opening formed in the forwardly extending portion 25 of the bracket 26 which extends down from the portion 25 and is secured to the arm 19 just rearwardly of the pin 23.

Between the bracket portion 25 and the collar 24 the spring 27 is tensed, normally to maintain the collar 24 in position against the arm 19, and therewith the pin 23 in lower position. The lower end of the pin 23 protrudes below the arm 19 and has secured at its lower end the transversely extending pin 28, the lateral ends of which are adapted to be engaged by the arms 29 and 30 of the gripping jaw members 31 and 32 secured to the front free ends of the arms 29 and 30.

The arms 29 and 30 are pivotally mounted at their rear ends on the shaft 33 secured to the lower bifurcated ends of the section 18 of the upright member 16. The pivotal connection between the arms 29 and 30 and the shaft 33 is such that it will permit lateral movement of the arms 29 and 30 relative to one another so as to permit the gripping jaw members 31 and 32 to approach one another and recede from one another in the act of gripping an article and again releasing the same.

The depending portion 20 extends at all times between the arms 29 and 30. For normally and yieldably maintaining the arms 29 and 30 in closed position or gripping position, the arms 29 and 30 at the rear ends of the gripping jaw members 31 and 32, as clearly illustrated in Fig. 7, have a pin 34 extending through them, which pin has at its outer free ends protruding beyond the gripping jaws 31 and 32 the nuts 35 and 36 to form abutments between which and the gripping jaw members 31 and 32, the coil springs 37 and 38 respectively are tensed. By means of these springs 37 and 38 as aforesaid the gripping jaw members 31 and 32 will be normally and yieldably maintained in closed or gripping position.

On the arms 29 and 30 and opposing one another, there are formed the cams 39 and 40 respectively which are adapted to register with the edges of the depending member 20. The depending member, as shown in Figs. 3, 4 and 5, is provided with a dimin-

ished portion 41 which graduates into the enlarged portion 42 through the outwardly flaring cam faces 43 and 44. When the arms 29 and 30 are rocked upwardly, the cams 39 and 40 will co-act with the cam faces 43 and 44 and spread apart the gripping jaw members 31 and 32, which will remain in open or spread apart position so long as the cams 39 and 40 ride on the edges of the enlarged portion 42 of the depending member 20.

Between the arms 29 and 30, there extends the horizontally extending portion 45 of the bent lever 46 which is pivoted at 47 to the shaft 33, the upwardly extending portion 48 of the bent lever extending up between the bifurcated portions of the section 18, and itself having a bifurcated end 49 to receive the end of the link 50 which is there pivotally connected to the arm 48 by the pin 51. At the forward end of the arm 45, and to the lower side thereof, there is secured the block 52 which is wider than the arm 45 and forms the stop shoulders 53 and 54 with the arm 45 as shown in Fig. 8, and has the lower laterally extending stop ledges 55 and 56. The shoulders 53 and 54 and ledges 55 and 56 are adapted to co-act with the recesses 57, Fig. 2, of the arms 29 and 30.

The link 50 will be intermittently actuated to transmit an intermittent actuation to the bent lever 46 in turn intermittently to actuate the gripping jaw members 31 and 32. In the present instance, the link 50 is pivotally connected to the lever 58, the screw 59 and slot 60 affording a ready adjustment to vary the throw to be transmitted to the gripping jaws 31 and 32, according to the size of tubes to be gripped and discharged.

The lever 58 is fixed on the shaft 61 mounted in the bearings 62 and 63 formed on the frame member 64. In the present instance, a rocking action is transmitted to the shaft 61 by means of the lever 65 fixed on the shaft 61, the free end of which is pivotally connected to the arm 66 fixed to the cam lever 67 which is fulcrumed at 68 to the frame and provided with a cam roller 69 co-acting with the cam wheel 70. The pump 7, it will be seen in Fig. 1, is connected intermittently to be opened by means of the lever 71 fixed to the shaft 72 connected to the spout not shown on the pump 7, which lever 71 is pivotally connected by the link 73 to the cam lever 67, so that, in the present instance, the toilet cream dispensing pump 7 will be operated from the same cam wheel 70 by which the gripping member 11 is operated.

The gripping faces of the gripping jaw members 31 and 32, as shown in Figs. 3, 4, 5 and 7, are provided with the vertically extending slots 74 and 75 having the out-

wardly flaring ends 76 and 77, at their lower ends as shown particularly in Figs. 3 and 4, to form guides for the edges of the bottom ends of the tubes to be gripped by the jaw members 31 and 32.

In the operation of the device, the tubes 6 to be filled will be placed in the containers 5 at about the station A shown in Fig. 1. The turntable 1 is timed intermittently to 10 rotate and then come to positions of rest. Upon the continued intermittent rotation of the turntable 1, after the tubes 6 are received by the containers 5, the tubes 6 will subsequently come to positions of rest 15 beneath the toilet cream dispenser 7, where the tubes 6 will be filled with the desired toilet cream, and the tubes 6 subsequently will arrive in positions of rest adjacent to the closing dies 8 and 9 where the closing dies 8 and 9 will be caused to engage the bottom ends of the tubes 6, form flanges therein and fold them over securely to close the bottom ends of the tubes 6, whereupon the tubes 6 will then be brought to positions 20 of rest under the gripping member 11.

When a tube 6 is brought into position for engagement by a gripping member 11 the jaw members 31 and 32 will descend, spaced apart as shown in Fig. 3, the arms 29 and 30 engaging the sides of the block 52 on the bent lever 46, and as the bottom end of a tube is positioned between the jaw members 31 and 32, when the arms 29 and 30 will engage the stop ears 21 and 22, the bent lever 46 will be timed to move still farther and cause the block 52 to descend still farther to slide down out of engagement with the arms 29 and 30, when the springs 37 and 38 will be free to press the jaw members 31 and 32 into engagement with the pointed ends of the closed bottom of the tube 6 being discharged.

After the tube 6 is so engaged by the jaw members 31 and 32, the bent lever 46 will be caused to return in its cycle of movement, and cause the arm 45 to ascend, when the arms 29 and 30 will be engaged by the shoulders 53 and 54 of the block 52, thereby causing the jaw members 31 and 32 to be raised, and since the tube 6 is being given a slight forward thrust as it is being so raised, as soon as the jaw members 31 and 32 approach the cam faces 43 and 44 of the depending member 20, the cams 39 and 40 will engage such cam faces 43 and 44, spread apart the jaw members 31 and 32 and permit the tube 6 to be thrust forwardly onto the chute 12. Then as the jaw members continue in their ascent, and the cams 39 and 40 engage the edges of the enlarged portion 42, the arms 29 and 30 will have engaged the pin 28, when the stop ledges 55 and 56 will be brought into engagement with the arms 29 and 30 and continue to raise the arms 29 and 30 against the tension of the spring 27.

When the link 50 is again caused to lower the arm 45, the arm 45 will tend to precede the arms 29 and 30, at which time the spring 27 will be free to depress the pin 23 and therewith the pin 28 to depress the arms 29 and 30, until after the arms 29 and 30 pass the cam faces 43 and 44, where the arms 29 and 30 will again engage the block 52 and by frictional engagement therewith be lowered the rest of the way by 75 means of the block 52 when a succeeding tube 6 will have been brought into position by the turntable 1 to be engaged by the jaw members 31 and 32 as above described.

It is obvious that various changes and modifications may be made to the details of construction without departing from the general spirit of the invention as set forth in the appended claims.

I claim:

1. In a device of the character described, the combination with a rotatable carrier having seats adjacent its periphery to receive containers and the like, of a horizontal shaft extending across said carrier, a pair of arms 90 pivotally secured to said shaft and terminating in jaws extending above said seats, means for actuating said arms to lower said jaws into engagement with the containers on said seats, means for swinging said arms toward one another to close said jaws when lowered to engage the containers disposed on said carrier, and means for raising said arms with the jaws so closed to pick up and discharge the containers from said carrier.

2. In a device of the character described, the combination with a rotatable carrier having seats adjacent its periphery to receive containers and the like, of a horizontal shaft 95 extending across said carrier, a pair of arms pivotally secured to said shaft and terminating in jaws integral with said arms, said jaws being actuatable above said seats, means for actuating said arms to lower said jaws into engagement with the containers on said carrier, means for closing said jaws when lowered to engage the containers disposed on said carrier, means for raising said arms with the jaws so closed to pick up the containers from said carrier, and cams 100 for opening said jaws when raised to discharge the containers from said jaws.

3. In a device of the character described, the combination with a movable turntable 110 for containers and the like, a shaft, jaws pivotally mounted on said shaft, cams in engagement with, and for opening said jaws and for holding said jaws open until they receive a container disposed on said carrier, said cams releasing said jaws after they descend into position for receiving a container, springs for normally closing said jaws when released to grip a container, and means for raising the jaws so closed to pick up and deliver a container from said carrier.

130

4. In a device of the character described, the combination with a carrier, for supporting tubes, of a discharging device disposed above the path of movement of the tubes on said carrier, and mounted to swing in a plane perpendicular to the path of movement 70 of the carrier, means for causing said discharging device to swing downwardly into engagement with the tubes disposed on said carrier and again rise, means for causing said device to grip a tube when 75 so descended and permit the tube to be removed from the carrier upon the ensuing ascent of the device, and means for causing said device to rise and simultaneously release the tube so removed from said carrier 80 to permit the discharge of the tube.
5. In a device of the character described, the combination with a carrier, of holders on said carrier for receiving toilet cream tubes, a shaft, jaws pivotally mounted on said 85 shaft, a bent lever, a depending arm, cam faces on said arms, means for raising said jaws into cooperative relation with said cam faces to open the same, means for holding the jaws open until they again descend and 90 receive containers disposed on said carrier, said cams releasing said jaws after they descend into position for receiving a container, springs for normally closing said jaws when 95 releasing to grip a container, and means for raising the jaws so closed to pick up and deliver a container from said carrier.
6. In a device of the character described, the combination with a rotatable carrier, of holders on said carrier for receiving toilet 100 cream tubes, arms extending outwardly from the center of said carrier, discharging jaws formed at the ends of said arms, and disposed above the path of movement of said 105 holders, means for causing said jaws to descend into engagement with the toilet cream tubes disposed in said holders and again rise, means for closing said jaws when so descended to grip a toilet cream tube and permit the tube to be removed out of its holder upon 110 the ensuing ascent of the jaws, and means for opening said jaws to permit the discharge of the tube so removed from its holder.
7. In a device of the character described, 115 the combination with a movable carrier, of holders on said carrier for receiving toilet cream tubes, pivotally mounted arms having jaws at their free ends disposed above the path of movement of said holders, means for causing said arms to swing to cause said 120 jaws to descend into engagement with the toilet cream tubes disposed in holders and again rise, means for closing said jaws to grip a toilet cream tube when so descended 125 and permit the tube to be removed out of its holder upon the ensuing ascent of the jaws, and means for opening said jaws to release the tube so removed out of its holder to permit discharging of the tube.
8. In a device of the character described, 130 the combination with a carrier, for supporting tubes, of a shaft, gripper members pivot-
9. In a device of the character described, the combination with a carrier for supporting tubes, of discharging jaws mounted to swing in a plane perpendicular to the path of movement of the carrier, means for causing said jaws successively to swing downwardly into engagement with the tubes disposed on said carrier, means for causing said jaws to remove from the carrier the tubes so engaged, and means for causing said jaws to rise and simultaneously release the tubes so removed from the carrier to permit the delivery of the tubes from the carrier.
10. In a device of the character described, the combination with a carrier, for supporting tubes, of a shaft, gripper members pivotally mounted on said shaft, a bent lever pivotally mounted on said shaft and having an arm extending between said gripper members, supporting stops on said arm on which said gripper members normally rest, means for oscillating said bent lever to cause said gripper members to descend and ascend, spreading stops on said arm for engaging said gripper members when opened to maintain them in open position, an upper spring for initially exercising a downward pressure on said gripper members to cause said gripper members positively to follow said arm when its descends, lateral springs for normally exercising lateral tension to cause said gripper members to close, a depending member, limiting stops on said depending member for limiting the downward movement of the gripper members, said arm descending further down than said gripper members descend so as to withdraw said spreading stops to permit said lateral springs to close said gripper members at the lowermost position of the gripper members there to grip a tube disposed on the carrier, cam faces on the depending member, and cams on said gripper members to be engaged by said cam faces to cause said gripper members to open as they ascend and permit the tube engaged to be delivered.
11. In a device of the character described, the combination with a carrier, for supporting tubes, of a shaft, gripper members pivot-

ally mounted on said shaft, lateral springs on said members for exercising a lateral tension on said gripper members normally to close the same, means for oscillating said gripper members, means for holding said gripper members spread apart as they descend; means for releasing said holding means at the lowermost position of the gripper members to permit the gripper members 5 to grip a tube on said carrier, a depending member, cam faces on the depending member, and cams on said gripper members to be engaged by said cam faces to cause said gripper members to open as they ascend 10 and permit the tube engaged to be delivered. 12. In a device of the character described, the combination with a carrier, for supporting tubes, of a shaft, gripper members pivotally mounted on said shaft, lateral springs 20 on said members for exercising a lateral tension on said gripper members normally to close the same, means for oscillating said gripper members, means for holding said gripper members spread apart as they descend, means for releasing said holding 25 means at the lowermost position of the gripper members to permit the gripper members to grip a tube on said carrier, and means for again spreading apart said gripper members as they ascend. 30

13. In a device of the class described, the combination with a support having a seat for a container, of a receiving platform to one side of said seat, a gripper pivotally secured at a point to the other side of said seat, means for swinging said gripper downwardly to grip the container located on said seat and again upwardly in the direction of said receiving platform to swing the gripped container toward said receiving platform and discharge it thereon, the gripper passing through a vertical plane in alignment with said receiving platform and seat. 35

14. In a device of the class described, the combination with a rotary carrier, there being 40 pockets in said carrier adjacent to the periphery thereof for supporting containers, a horizontal shaft disposed inwardly from the periphery of said carrier, arms pivotally mounted on said shaft and forming gripping jaws at their free ends disposed above the path of movement of said pockets, means for swinging said arms downwardly to cause said jaws to receive a container, means for causing said jaws to close when lowered, and means for thereupon causing said jaws 45 to ascend and open while rising to discharge the container received. 50 55

EDWARD E. KALLENBACH.
